GRATE STRUCTURE

John W. Hulson, Keokuk, Iowa

Application June 1, 1934, Serial No. 728,582

10 Claims. (Cl. 126—168)

The invention relates to grate structures of the general type having parallel fire-supporting ridges, grooves extending longitudinally between said ridges to receive and disperse the draught air, and tuyère openings for delivering draught air to said grooves. With such grates, the ridges are prone to fuse and scale, particularly in the higher range of draughts and when the grate is subjected to the "soaking temperature" en- 5 countered when very little draught air is being supplied, for instance, during "stand by" service on stationary boilers and locomotives held under fire.

The principal object of the present invention 10 is to overcome the above difficulty by the provision of an improved structure in which the air discharged from the grooves flows upwardly and laterally from them in contact with the ridges, thereby so bathing said ridges with the ingoing air as to maintain them at a safe temperature.

A further object is to provide for imparting a whirling motion to the air as it leaves the grooves thereby more intimately mixing it with the combustible gases to better support combustion.

A still further aim is to provide, in accordance with accepted practice, for constructing the improved grate from finger bars and finger plates.

With the foregoing in view, the invention re- 20 sides in the novel subject matter hereinafter described and claimed, description being accomplished by reference to the accompanying drawings.

Fig. 1 is a partial plan view partly broken away 25 and in horizontal section.

Fig. 2 is a side elevation of one of the finger plates, the finger bar being shown in vertical section.

Fig. 3 is a vertical sectional view on line 3—3 30 of Fig. 1.

Fig. 4 is a similar view to Fig. 2 but showing a different form of construction.

Fig. 5 is a vertical sectional view on line 5—5 35 of Fig. 4.

40 In the form of construction shown in Figs. 1 to 3, a portion of a grate is shown including a plurality of finger bars such as 10 and a plurality of contacting finger plates 11 mounted upon each bar, the various bars and plates being preferably

50 connected with each other in the manner disclosed in U. S. Patent No. 1,500,920, issued July 8, 1924 to myself and William F. Bradley.

Each finger plate 11 includes an elongated fire- 55 supporting ridge 12 which is transversely con- vex as denoted at 13. Integral with the opposite

sides of the ridge 12 respectively and projecting laterally from the base portion of said ridge are two flanges 14 of identical size and shape, said flanges extending throughout the length of the ridge 12. Integral with the inner portions of these flanges 14 and the base portion of the ridge 12 is a central vertical longitudinal supporting web 15 which is provided with a suitable hub 16 mounted upon the finger bar 10.

The ridge 12 is of a width considerably greater 10 than the thickness of the web 15 so that both said ridge and the flanges 14 project laterally in opposite directions from said web. In these projecting portions, tuyère openings 17 are formed 15 for conducting draught air from the ash-pit into the air-receiving grooves G which are formed between the ridges 12 when the various finger plates 11 are positioned upon the finger bar 10. The air discharged into the grooves G is discharged 20 upwardly and laterally from these grooves, and due to the transverse convexity of the ridges 12, the air will flow laterally over and constantly bathe said ridges, keeping them at such a temperature as to prevent fusing and scaling. To facilitate this flow of air, each ridge 25 12 is provided with a plurality of transverse grooves 18 which preferably lead from its opposite sides to points near the longitudinal center of the ridge.

It will be observed that the delivery ends of 30 the tuyère openings 17 are in opposed relation at opposite sides of the grooves G so that the discharging streams of draught air strike each other head-on. This causes dissipation of the streams and the discharging air flows not only directly 35 upward from the grooves G but laterally along and in contact with the convex surfaces 13 of the ridges 12. Preferably, alternate tuyère openings at either side of each groove G are relatively 40 large and small as shown, and the relatively small openings at one side of each groove are directly opposite the relatively large openings at the opposite side thereof. By thus admitting opposing streams of different sizes, I have found that the air is violently whirled as it is discharged from 45 the grooves G, thereby facilitating intimate mixture with the combustible gases and insuring better combustion. This difference in relative sizes of opposed tuyère openings, need not be carried out entirely throughout the length of each finger 50 plate 11, in which connection it is to be observed that the relation of relatively large and small openings is not shown at the central portions of the various finger plates, to provide a more even distribution of metal and a stronger structure. 55

In Figs. 4 and 5, the finger plates 19 are very similar to those shown in my U. S. Patent No. 1,715,294 of May 28, 1929. Each plate is provided with a relatively high step 20 and a comparatively low step 21 so that when the plates are assembled, they provide the grate with longitudinal fire-supporting ridges and with draught air receiving and dispersing grooves between said ridges. The high steps 20 have the corners thereof toward the grooves rounded as denoted at 22 so that each ridge is given a transversely convex form for the same purpose as above described. The openings 23 which admit the draught air into the grooves G' are preferably alternately large and small with the large openings at either side of each groove directly opposed to the small openings at the opposite side thereof, for whirling the air as above explained.

It will be seen from the foregoing that I have provided an exceptionally simple and inexpensive construction which will not only overcome the prior difficulty with regard to fusing and scaling of the ridges, but will promote more thorough combustion. As excellent results have been obtained from the specific constructions shown, they are preferably followed. However, within the scope of the invention as claimed, variations may of course be made.

I claim:

1. A grate having parallel fire-supporting ridges, air grooves extending longitudinally between said ridges, and tuyère openings at opposite sides of said grooves for conducting draft air into said grooves and forcing said air upwardly and laterally from said grooves, the tuyère openings at each side of each groove being alternately large and small with the large openings opposed to the small openings to whirl the air as it discharges from the grooves, said ridges being transversely convex to allow the air to completely bathe said ridges as it discharges upwardly and laterally from said grooves.

2. A grate having parallel fire-supporting ridges, air grooves extending longitudinally between said ridges, and tuyère openings at opposite sides of said grooves for conducting draft air into said grooves and forcing said air upwardly and laterally from said grooves, the tuyère openings at each side of each groove being alternately large and small, with the large openings opposed to the small openings to whirl the air as it discharges from the grooves, said ridges being transversely convex and having transverse air conducting grooves leading from opposite sides thereof, allowing the air to completely bathe said ridges as it discharges upwardly and laterally from said grooves.

3. In a grate, a finger bar, a plurality of contacting finger plates mounted thereon, said finger plates being shaped to provide parallel fire-supporting ridges and air conducting grooves extending longitudinally between said ridges, said finger plates having tuyère openings at opposite sides

of said grooves for conducting draft air into said grooves and forcing it upwardly and laterally from said grooves, the tuyère openings at each side of each groove being alternately large and small with the large openings opposed to the small openings to whirl the air as it discharges from the grooves, said ridges being transversely convex to allow the air to completely bathe said ridges as it discharges upwardly and laterally from said grooves.

4. In a grate, a finger bar, and a plurality of contacting finger plates mounted thereon, said finger plates being shaped to provide parallel fire-supporting ridges and air conducting grooves extending longitudinally between said ridges, said finger plates having tuyère openings at opposite sides of said grooves for conducting draft air into said grooves and forcing it upwardly and laterally from said grooves, the tuyère openings at each side of each groove being alternately large and small with the large openings opposed to the small openings to whirl the air as it discharges from the grooves, said ridges being transversely convex and having transverse air-conducting grooves leading from opposite sides thereof, allowing the air to completely bathe said ridges as it discharges upwardly and laterally from said grooves.

5. A finger plate comprising an elongated fire-supporting ridge having opposite substantially vertical longitudinal sides, two longitudinal flanges integral with said opposite sides of said ridge respectively and projecting laterally from the base portion of said ridge, and a central vertical longitudinal supporting web integral with said base portion and said flanges, said ridge being of a width considerably greater than the transverse thickness of said web, said flanges and said base portion of said ridge being formed with tuyère openings leading from the lower sides of said flanges through said opposite sides of said ridge.

6. A structure as specified in claim 5; the upper side of said ridge being transversely convex.

7. A structure as specified in claim 5; the upper side of said ridge being transversely convex and having transverse air conducting grooves leading from said opposite sides of said ridge.

8. A structure as specified in claim 5; said tuyère openings being alternately large and small for the purpose set forth.

9. A structure as specified in claim 5; the upper side of said ridge being transversely convex, said tuyère openings being alternately large and small for the purpose set forth.

10. A structure as specified in claim 5; the upper side of said ridge being transversely convex and having transverse air conducting grooves leading from said opposite sides of said ridge, said tuyère openings being alternately large and small for the purpose set forth.

JOHN W. HULSON.
